UNITED STATES PATENT OFFICE.

JEAN D. SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS OF DEPHLEGMATION.

Application filed March 25, 1925. Serial No. 18,187.

This invention relates to improvements in a process and apparatus of dephlegmation, and refers more particularly to the treatment of vapors in a dephlegmator forming 5 part of a system for the treatment of hydrocarbon oils.

In the specific embodiment of the present invention, the vapors released from hydrocarbon oil which has been subjected to high 10 heat, are introduced into the interior of the dephlegmator and there subjected to dephlegmation. Portions of said vapors will condense as reflux condensate, and the remaining uncondensed portions after passage 15 through the dephlegmator, are withdrawn, condensed and collected as distillate. The capacity and efficiency of the dephlegmator are carefully controlled and regulated by regulating the point of introduction of 20 the vapors and controlling the point of withdrawal of liquid reflux condensate, which liquid reflux is maintained in a pool in the lower end of the dephlegmator, the depth of said pool being carefully controlled by controlling the point at which reflux is withdrawn 25 from said pool.

In the drawing, the single figure is a side elevational view, partly in vertical section of a dephlegmator with its associated connections.

Referring in detail to the drawing, 1 designates as a whole the dephlegmator which may take the form of a steel drum disposed in a vertical plane having the rounded lower 35 end 2 and upper detachable cap 3, from which extends the vapor outlet 4 in which is interposed the valve 5. Communicating with the lower end 2 of the dephlegmator is the reflux leg 6 of restricted diameter, in which is interposed the valve 7. An upward extension 8 projects into the interior of the chamber from the lower end 2 having a spaced cap portion 9 disposed thereabove. Suitable baffles or perforated pans 40 10 which are of standard construction, are superimposed in the interior of the chamber.

Referring now to some of the features of the present invention, the hydrocarbon vapors which have been released from a body 50 of hydrocarbon oil which has been subjected to a high conversion temperature, passes upwardly through the vapor inlet pipe 11. This vapor inlet pipe 11 is provided with branches 12, 12' and 12'' controlled by valves 55 13, 13' and 13'' respectively, said branches

being preferably superimposed and connected into the side wall of the chamber 1 at varying heights. The vapors in their passage upward through the dephlegmator are retarded by the baffles or perforated pans 10, 60 and a large percentage of the heavier ends or fractions will condense therein and fall to the bottom or lower end 2 of said dephlegmator, the vapors still remaining uncondensed after passage through the dephlegmator being discharged through the vapor outlet 4.

As a feature of the present invention, instead of allowing the liquid reflux condensate to drain into the reflux leg 6 and be withdrawn from the system or returned to the body of oil being subjected to the conversion temperature as is usually the practice, the reflux condensate may collect in a pool such as shown at 8. By regulating the extent to which the pipe 8 projects into the interior of the chamber through the bottom 2, the level of the pool of reflux condensate designated at A may be carefully regulated. When the level is maintained at A, only 75 the branch 12 preferably discharges vapors into the interior of the chamber 1, the valve 13 being open, and the valves 13' and 13'' in the branches 12' and 12'' being closed. The reflux condensate overflowing through the 80 pipe 8 passes down through the leg 6, the valve 7 being open, into the enlarged portion 14 of the reflux leg 6, discharging into the suction side of the pump 15 which may discharge said liquid condensate through the 85 line 16 regulated by the valve 17 to storage, or through the line 18 regulated by the valve 19 to be returned to the body of oil being heated. It will be understood that the dephlegmator may be maintained under a 90 superatmospheric pressure.

Depending upon the characteristics of the vapors released when treating certain kinds of oil, it may be desirable to maintain the pool of liquid reflux condensate accumulating in the lower end of the chamber 1 at a much greater depth than that shown at A. In this event the valve 7 is totally or partially closed, and the level of the pool carried at B. Regulated portions of the liquid condensate may be withdrawn from the pool of oil maintained at the level B through the drawoff 20 controlled by valve 21, discharging into the drawoff 22, which drawoff 22 discharges into the enlarged portion 110

14 of the reflux leg communicating with the pump 15.

In the same manner when dephlegmating vapors released from other oils containing 5 different characteristics, it may be desirable to carry the level of the pool of reflux condensate at a point, say, midway of the dephlegmator at a level designated as C. In this event, liquid condensate may be withdrawn 10 from the pool when it is maintained up to the level C through the line 23 controlled by the valve 24, which line 23 communicates with the line 22, heretofore described, returning the said liquid condensate 15 to the enlarged portion 14 of the reflux leg, which in turn communicates with the pump 15.

Raw oil may be introduced to the interior 20 of the chamber through the raw oil inlet line 25 in which is interposed valve 26, terminating in the spray or rose 27, said raw oil preferably being introduced at a point immediately adjacent the upper end of the dephlegmator.

25 In the same manner, regulated portions of the distillate produced by condensing the vapors discharging through the line 4, may be returned through the distillate inlet line 28 controlled by the valve 29, which line 28 terminates in the rose or spray 30 in the interior of the dephlegmator 1. The purpose 30 of introducing the raw oil and distillate is to control the temperature of the vapors discharging through the vapor outlet 4 to 25 produce a cooling and condensing of the heavier fractions of the vapors.

It is to be noted that the point of vapor introduction to the interior of the dephlegmator is slightly above the level of the pool 40 of reflux condensate maintained therein. In other words, if the level of the pool of liquid condensate is maintained at A, the vapors will discharge through the branch 12, the valve 13 being open, and the valves 13' and 45 13'' closed. Also valve 7 can be opened, and valves 21 and 24 closed. It will be apparent that the same method of operation will be followed as the vapors are introduced at successively higher points, the valves being suitably regulated as hereinbefore described.

50 By means of the present invention, the capacity of the dephlegmator is carefully regulated, according to the characteristics of the vapors entering and leaving the dephlegmator by controlling the level of the 55 pool of liquid reflux maintained in the lower end thereof. The advantage of being able to do this, will be at once apparent, as it is not possible to change the capacities of the present dephlegmators now in use, and it 60 would not be practical to substitute dephlegmators of differing capacities in treating different kinds of oils. It is of course, apparent that as the depth of the

pool of liquid reflux is increased, that the 65 dephlegmating capacity is decreased. It is pointed out that it is not actually necessary to superimpose the vapor lines or reflux drawoff lines, as they may be placed at points of varying height. 70

The apparatus is very flexible in operation, and is productive of extremely good results.

I claim as my invention:

1. A process of dephlegmating hydrocarbon oil vapors, consisting in introducing vapors released from liquid hydrocarbon oil subjected to a conversion temperature into a vertical dephlegmator, maintaining a pool of liquid reflux condensate in the lower portion thereof, controlling the depth of the pool by regulating the point of withdrawal of the condensate from said pool, regulating the point of introduction of said vapors dependent upon the depth of the pool, thus controlling the capacity of said dephlegmator, withdrawing the uncondensed vapors from the upper portion of the dephlegmator. 80

2. A process of dephlegmating hydrocarbon oil vapors, consisting in introducing vapors released from liquid hydrocarbon oil subjected to a conversion temperature into a vertical dephlegmator, maintaining a pool of liquid reflux condensate in the lower portion thereof, controlling the depth of the pool by regulating the point of withdrawal of the condensate from said pool, in concurrently regulating the point of introduction of said vapors, thus controlling the capacity of said dephlegmator, withdrawing the uncondensed vapors from the upper portion of the dephlegmator, and maintaining the contents of the dephlegmator under a superatmospheric pressure. 90

3. A process of dephlegmating hydrocarbon oil vapors, consisting in introducing vapors released from liquid hydrocarbon oil subjected to a conversion temperature into a vertical dephlegmator, maintaining a pool of liquid reflux condensate in the lower portion thereof, controlling the depth of the pool by regulating the point of withdrawal of the condensate from said pool, in concurrently varying the point of introduction of said vapors to correspond with the changed depth of the pool, thus controlling the capacity of said dephlegmator, withdrawing the uncondensed vapors from the upper portion of the dephlegmator, and maintaining the contents of the dephlegmator under a superatmospheric pressure, introducing a liquid cooling medium to the dephlegmator and physically commingling said medium with the contents of the dephlegmator. 110

4. A dephlegmator for use with oil treating apparatus, comprising a vertically disposed chamber, a vapor outlet adjacent its upper end, a plurality of valved vapor inlets 115 120 125

- disposed at various heights on the side wall of said chamber discharging the vapors at regulated heights into the interior of said chamber, and a plurality of valved outlets 5 disposed at varying heights on said chamber through any one of which the liquid reflux condensate may be withdrawn to maintain a controlled level in said dephlegmator, means adjacent the upper end of said chamber for introducing liquid cooling medium to the interior thereof.
5. A dephlegmator for use with oil treating apparatus, comprising a vertically disposed chamber, a vapor outlet adjacent its upper end, a plurality of superimposed valved vapor inlets disposed at various heights on the side wall of said chamber discharging the vapors at regulated heights into the interior of said chamber, and a plurality 10 of superimposed valved outlets disposed at varying heights on said chamber through any one of which the liquid reflux condensate may be withdrawn to maintain a control liquid level in said dephlegmator, means adjacent the upper end of said chamber for introducing liquid cooling medium to the interior thereof.
6. A method for controlling the capacity of a dephlegmating column for dephlegmating hydrocarbon oil vapors, consisting in maintaining a predetermined volume of reflux condensate in the dephlegmating column by withdrawing the reflux condensate from the dephlegmating column at predetermined vertically spaced points thereof and in introducing the vapors to the dephlegmating column at a point above the liquid level of the reflux condensate maintained in the dephlegmating column, and in varying the 15 point at which the vapors are introduced to the dephlegmating column when the liquid level of the reflux condensate in the dephlegmating column is varied.
7. An apparatus for dephlegmating hydrocarbon oil vapors, comprising an elongated vertically disposed column, a plurality of vertically spaced vapor inlets communicating with said dephlegmating column, means for introducing vapors to said dephlegmating column through any one of said vapor inlets, means for taking off dephlegmated vapors from said column, a plurality of vertically spaced reflux draw-off lines communicating with said dephlegmating column, means for drawing off reflux 20 through any one of said reflux draw-off lines, to thereby maintain a predetermined liquid level in said dephlegmating column, to control the dephlegmating capacity thereof.
8. An apparatus for dephlegmating hydrocarbon oil vapors, comprising a vertically disposed dephlegmating column, a plurality of vertically spaced vapor inlet lines communicating with said column, means for independently introducing vapors to said dephlegmating column through any one of said vapor inlet lines, a pump for conveying reflux condensate away from said column, a plurality of vertically spaced reflux draw-off lines communicating with said dephlegmating column and having a common communication with said pump, means for taking off reflux condensate through any one of said draw-off lines, to maintain a predetermined liquid level in said dephlegmating column, means for taking off dephlegmated vapors from said dephlegmating column, and means for supplying a cooling agent to said dephlegmating column.

JEAN D. SEGUIN.
